UNITED STATES PATENT OFFICE.

JOHN A. HARTVIG, OF CHICAGO, AND ARTHUR A. McLAURIN, OF FOREST PARK, ILLINOIS.

HAIR CURLER.

Application filed November 17, 1925. Serial No. 69,647.

The present invention relates to hair curlers or wavers.

The object is to provide a simple structure in which any amount of hair under the maximum capacity may be placed on the curler and effectively held in place, while viewed from another aspect the curler will be retained in position on the head of the wearer. In this respect a serious difficulty and objection to the type of curler or waver is overcome, for unless a predetermined amount of hair is secured there is always danger of the curler becoming unfastened.

An embodiment of the invention is illustrated in the accompanying drawings, wherein:

Figure 1 is a perspective view,

Figure 2 is a plan view,

Figure 3 is a cross sectional view taken 20 on the line 3—3 of Figure 2,

Figure 4 is a perspective view showing the curler or waver opened.

In the embodiment disclosed, an elongated cylindrical body 5 is employed, which may 25 be of celluloid, glass or other suitable material. One end of this body is perforated, as shown at 6. In this perforation is journaled one end 7 of a holding loop. The loop is preferably formed of resilient wire having 30 side arms 8 diverging from the pivoted end 7 and having their widely spaced apart ends connected by a cross bar 9. This cross bar is preferably formed by the inturned terminals of the wire engaged in a coupling 10 that permanently secures them together. Slidably mounted on the divergent side arms 35 8 is a keeper in the form of a continuous loop strap of metal, designated 11 that is thus permanently and slidably mounted on 40 the side arms. Intermediate portions of this loop are pinched together, forming outer guideways 12 for the side arms 8 and an enlarged central socket 13 that receives the free end of the body 5.

45 As clearly shown, the side arms 8 extend beyond the free end of the body 5 a sufficient distance to permit the keeper to be disengaged from the body, yet said keeper is permanently held on the side arms by the 50 cross bar 9—10.

In using the device the body is freed from the keeper, as illustrated in Figure 4, and the hair wrapped upon said body, after which the body is placed in line between the

side arms, and the keeper 11 moved down 55 until it engages with the coil of hair. When so positioned, as illustrated in Figure 1, the keeper will be effectively held in place by contact with the hair, and by frictional engagement with the side arms, this being due 60 to the divergent relation of said side arms and their frictional contact with the ends of the keeper. Consequently the parts will retain their operative positions and this will be true, irrespective of the amount of hair 65 wrapped upon the body, because the keeper can always be moved up to the hair. The danger therefore of the keeper sliding off the end of the body and releasing the same is substantially obviated.

70 From the foregoing, it is thought that the construction, operation and many advantages of the herein described invention will be apparent to those skilled in the art, without further description, and it will be understood that various changes in the size, shape, proportion and minor details of construction, may be resorted to without departing from the spirit or sacrificing any of the advantages of the invention.

75 What we claim is:

80 A hair curler comprising an elongated body on which the hair is wrapped, a retaining loop pivoted at one end to one end of the body and having side arms that diverge from the pivoted end to the opposite end and are adapted to lie alongside opposite sides of the body and extended beyond the same, a cross bar of materially greater length than the thickness of the body connecting the free 85 ends of said side arms at a point beyond the free end of the body and holding them permanently in divergent relation and spaced from the body, and a keeper loop surrounding and frictionally sliding on the side arms, 90 said keeper loop being movable on the side arms between a position beyond the free end of the body and capable of unobstructed movement along said body, and said loop having portions inwardly crimped to prevent its detachment from the side arms and forming a socket between the side arms that 95 slidably receive the body.

100 In testimony whereof, we affix our signatures.

JOHN A. HARTVIG.
ARTHUR A. McLAURIN.
